WORM GEARING

Andrew B. Crichton, Jr., Johnstown, Pa., and Carl G. Wennerstrom, Chicago, Ill., assignors to The Crichton Company, Johnstown, Pa., a corporation of Delaware

Application September 20, 1950, Serial No. 185,884

5 Claims. (Cl. 74—425)

The present invention relates to a power or speed increase take-off unit or assembly adapted but not necessarily intended for removable interposition between a drill head or other device and a "short wall coal cutter" which drives and supports it generally like the speed increase take-off unit or assembly disclosed as part of our pending application for patent, Ser. No. 21,893, filed April 19, 1948, entitled Power Take-Off System and Apparatus, now matured into Patent No. 2,645,944, issued July 21, 1953.

While it is aimed to provide such a structure which attains the ends and possesses the advantages set forth in said application, it is particularly aimed to provide a novel construction especially wherein the power and take-off shafts are disposed at a right-angle to each other, one embodying a novel safety clutch means adapted to automatically yield or slip upon encountering predetermined resistance, a construction wherein power may be taken from the take-off shaft at a plurality of locations, and a construction wherein such latter shaft in particular and all parts as a whole are embodied in an exceedingly sturdy, compact and durable unit.

Various additional objects and advantages will be pointed out hereinafter, and otherwise become apparent from a consideration of the description following, taken in connection with the accompanying drawings illustrating an operative embodiment.

In said drawings:

Fig. 1 is a side elevation of the improved unit shown attached to a fragment of a "short wall coal cutter";

Fig. 2 is a view of the parts of Fig. 1 primarily in plan, but partly broken away and in section to disclose details;

Fig. 3 is a vertical sectional view taken on the plane of lines 3—3 applied to Figs. 1 and 4; and

Fig. 4 is a vertical sectional view taken on the line 4—4 applied to Fig. 3.

Referring specifically to the drawings, wherein like reference characters designate like or similar parts, the unit or assembly includes a suitable case 10 preferably consisting of a main section 11, an end plate 12, and a side plate or wall 13, all suitably and separably secured together. Extending into said casing, through its rear wall is a power receiving main shaft 15 adapted to be rotated or driven by an input or power take-off shaft to which it is coupled or fastened in any suitable manner according to the particular machine used as a source of power.

The instant construction is especially useful though not restricted to such employment, like the take-off assembly or unit disclosed in our pending application, Ser. No. 21,893, aforesaid, and thus the shaft 15 is adapted to be driven from a "short wall coal cutter" fragmentarily suggested at C, and may be part of or an extension of a take-off shaft or other driven part thereof. On the other hand, said input shaft 15 may be a shaft driven from and separably attached to the take-off shaft of the "short wall coal cutter" C, such as the shaft illustrated at 28 in said application, Ser. No. 21,893. Through the mecha-

2

nism to be later specifically described, the input power is used to drive or to operate an output shaft O disposed at a right-angle thereto.

Said power-receiving main shaft 15 is stepped and journalled in ball bearing devices 16 and 17 suitably seated in enlargements 18 and 19 of the casing section 11 and wall 13. A seal 20, also mounted by enlargements 18, surrounds shaft 15. On one side of bearing device 17 a washer 21 is applied to shaft 15, while on the other side a retaining snap ring 22 engages a groove of the shaft.

Loose or journalled on main shaft 15 is a worm wheel 23 to which is integrally welded or otherwise secured, a clutch head in the form of a plate or flange 24, with which coacts a clutch head in the form of a plate or flange 25 keyed or otherwise rigidly connected to main shaft 15 as at 26. One of said plates or flanges 25 and 26, for instance the former in recesses 27, houses one or more clutch pins 28 having conical heads 29 normally engaging conical recesses 30 of the plate or flange 24, and so urged by expansive coil-springs 31 abutting plate 25 and the heads 29 and surrounding shanks 32 of said pins guided in adjacent openings 33 of plate 25.

Above power-receiving main shaft 15 and at a right-angle thereto is an intermediate shaft 34, parallel to output shaft O, embodying a worm 35 enmeshed with the teeth of worm wheel 23. Said intermediate shaft 34 and parts directly associated therewith are insertable through the opening of the casing normally covered by plate 12. One end of such shaft 34 (Fig. 3) is journalled at 36 in the adjacent wall of the casing and at a location spaced therefrom; such shaft is journalled in a ball bearing device 38 mounted in an internal web or wall 39 of casing section 11. Said ball bearing device 38 at one side abuts a flange 40 on said shaft 34 and its other side is overlapped by a ring nut 41 screw-threaded at 42 to such shaft. A flange 43 and removable ring 44 specifically position bearing device 38 in said web 39.

Keyed on intermediate shaft 34 at 45 between plate 12 and web 39 is a pinion or gear wheel 46, which is enmeshed with a pinion or gear wheel 47 fast on the previously mentioned output shaft O.

Power is selectively taken off either end of output shaft O as suggested by the flexible shafting dotted at 48 and may be used for operating a drill head in coal mining as disclosed in our previously mentioned pending application, but at the same time may equally well be used for general purposes, such as to operate one or more faces or cross-cut conveyors, portable rock dusters, hoists, saws and the like. Said flexible shafting 48 extends into and around sockets 49 and 50 and is suitably coupled to blades 51 or otherwise to shaft O. Socket 49 is fixed to plate 12 and socket 50 is fixed to casing section 11. Reduced ends 52 and 53 of said shaft 34 are journalled in webs 54 of said sockets 49 and 50. Needle bearing devices 55 carried by socket 50 and web 39 directly journal said shaft O. Washers 56, 57 and 58 position said pinion 47 on the reduced portion 52 in contact with shoulder 59.

Any suitable means may be provided to prevent rotation of the instant unit as a whole with shaft 15. At opposite ends of casing 10, as on the closed end wall of section 11 and end plate 12, are bosses 60 which slidably mounted manually operable clutch bolts 61 urge toward sockets 49 and 50, respectively, by coacting expansive springs 62 to separably overlap a shoulder 63 on the flexible shafting 48.

Reverting to springs 31, they are adapted to yield at a predetermined degree of tension, as a safety measure, so that the drill-head and drill or the like coupled to flexible shafting 48 in encountering undue resistance cannot twist the arms and body of the operator when using the same.

In use, the power-receiving main or input shaft 15 being driven by the "short wall coal cutter" C or otherwise, will in turn rotate flange or plate 27 rigid thereon and through the coupling pins 28 normally rotate flange 24 and worm-wheel 23 unitarily therewith. Since worm-wheel 23 enmeshes with worm 35, it drives intermediate gear-shaft 34, gears 46 and 47, output shaft O and flexible shafting 48, and accordingly the drill-head or equivalent. Since springs 31 are of a predetermined known degree of tension, clutch pins 33 will automatically yield upon the drill head or equivalent encountering undue resistance as a safety measure as previously explained. In such event, the undue torque causes the coacting conical surfaces of the heads 29 and walls of recesses 30 to slide the clutch pins 28 out of recesses 30, overcoming the action of spring 31, and thus unclutching the heads 24 and 25 so that shaft 15 will rotate freely within worm wheel 23 and not drive it.

Various changes may be resorted to, provided they fall within the spirit and scope of the invention as defined by the appended claims.

What is claimed is:

1. A power take-off assembly comprising a casing, a power input shaft journaled therein, a gear on the latter and driven thereby, bearings for said shaft between which said gear is disposed, a second shaft, said second shaft having its axis at a different elevation from said input shaft and disposed approximately at right-angles thereto, a gear enmeshed with said first gear and disposed in driving relation to said second shaft, said casing having an opening at one wall thereof, a web inwardly of said wall, said second shaft being journaled in said web and in a wall of said casing in spaced relation to the web, a plate closing said opening, an output shaft journaled in said web, gearing between the second-mentioned and output shafts disposed in the casing between said web and said plate, and a socket mounted in one end of said casing and in which said output shaft is journaled, and adjacent which it is adapted for attachment to the element to be driven.

2. A power take-off assembly comprising a casing, a power input shaft journaled therein, a gear on the latter and driven thereby, bearings for said shaft between which said gear is disposed, a second shaft, said second shaft having its axis at a different elevation from said input shaft and disposed approximately at right-angles thereto, a gear enmeshed with said first gear and disposed in driving relation to said second shaft, said casing having an opening at one wall thereof, a web inwardly of said wall, said second shaft being journaled in said web and in a wall of said casing in spaced relation to the web, a plate closing said opening, an output shaft journaled in said web, gearing between the second-mentioned and output shafts disposed in the casing between said web and said

10
15

plate, and aligned sockets, one mounted in said plate and the other in the wall of the casing opposite thereto, said sockets having webs in which said output shaft is journaled.

3. A power take-off assembly comprising a casing, a power input shaft journaled therein, a worm-gear on the latter and driven thereby, bearings for said shaft between which said gear is disposed, a second shaft, said second shaft having its axis at a different elevation from said input shaft and disposed approximately at right-angles thereto, said second shaft having a worm enmeshed with said worm-gear, bearings for said second shaft between which said worm is disposed, said casing having an opening at one wall thereof and a web inwardly of said wall, said second shaft being journaled in said web and in a wall of said casing in spaced relation to the web, a plate closing said opening, an output shaft journaled in said web, and a gearing between the second-mentioned and output shafts disposed in the casing between said web and said plate.

4. A power take-off assembly comprising a casing, anti-friction devices journaled in said casing in spaced relation, a power input shaft journaled in said casing and extending exteriorly thereof and attachable to a source of power, a worm gear through which said shaft extends, said worm gear being disposed between said bearing devices, a shaft disposed above and at a right-angle to the first mentioned shaft having a worm enmeshed with said worm gear, said casing having an opening at a wall thereof, and a web inwardly of said wall, said second-mentioned shaft being journaled in said web, a plate closing said opening, an output shaft journaled in said web in parallelism to the first-mentioned shaft, and gearing between the second-mentioned and output shafts disposed in the casing between said web and said plate.

5. A power take-off assembly according to claim 4 having aligned sockets mounted one in said plate and one in the wall of the casing opposite thereto, said sockets having webs in which said output shaft is journaled.
